UNITED STATES PATENT OFFICE

EVA M. REESE, OF CANTON, OHIO

COMBINATION SUPPORTING GARMENT

Application filed July 29, 1932. Serial No. 625,839.

My invention relates to garments for bracing and/or supporting various parts of the body of the wearer, such as the back, the abdomen, and the bust, and the present invention is a continuation in part of common subject matter set forth in my prior application for patent for combination supporting garments, filed March 4, 1931, Serial No. 519,919.

Each user of a bracing or supporting garment has particular requirements, depending on the particular age, size, and physical condition of the user.

The portions of the body above the abdomen are so heavy that when the shoulders droop, the abdomen sags, and incorrect posture results.

In order to overcome such incorrect posture, it is desirable to provide support as may be required for the back and/or front portions of the chest and for the back and/or front portions of the abdominal regions.

One person may require a brace back support member and a front hose support member, while another person may require an abdominal and hip support member, a bust support member, and a waist back support member.

It is particularly desirable that brace back support members and waist back support members be adjustable and yielding, so as to accommodate themselves to the varying physical characteristics of users.

The objects of the present improvements include the provision of a plurality of improved selectively interconnecting bracing, supporting, and covering members, each adapted for supporting, bracing, or covering a particular part of the body, or for supporting other members, and some of the members being adjustable and yielding, whereby the particular requirements of each individual user may be attained by selected combinations of the several members.

The foregoing and other objects are attained by the garments, members, parts, improvements, and combinations, which comprise the present invention, and the nature of which is set forth in the following general statement, and preferred embodiments of which are set forth in the following descrip-

tion, and which are particularly and distinctly pointed out and set forth in the appended claims forming part hereof.

In general terms the improved supporting garments include an adjustable brace back member with yielding connecting means, a adjustable waist back member with yielding connecting means, a combined hip and abdominal supporting member, a front hose supporting member, and a combined bust, hose, and abdominal supporting member, together with selective connecting means, whereby either the brace back member or the waist back member may be used in combination with any one of several of the other members for providing suitable bracing and support for any individual wearer.

Preferred embodiments of the improved supporting garments in several different combinations are illustrated in the accompanying drawings forming part hereof, in which

Fig. 1 is a fragmentary side perspective view illustrating a woman wearing one combination of the members, including the adjustable brace back member, and the front hose supporting member;

Fig. 2, a fragmentary back perspective view thereof;

Fig. 3, a fragmentary perspective view illustrating a man wearing one of the adjustable brace back members, and connecting means enabling the use of the same with trousers;

Fig. 4, a view illustrating a preferred buckle strap and eyelet connecting means for use in the arrangement illustrated in Fig. 3;

Fig. 5, a detached outside view with some of the parts disconnected illustrating the details of the construction and arrangement of the improved brace back member hereof;

Fig. 6, a fragmentary perspective view illustrating a woman wearing another combination of the members, including the adjustable waist back member, and the combined hip and abdominal supporting member;

Fig. 7, a fragmentary front perspective view of a woman wearing still another combination of the members, including the members of the combination of Fig. 6, together

with the combined bust, hose, and abdominal supporting member;

Fig. 8, a back view thereof;

Fig. 9, a detached outside view illustrating the improved waist back member with certain parts thereof disconnected; and

Fig. 10, a detached outside view of the improved combined abdominal and hip supporting member.

10 Similar numerals refer to similar parts throughout the several views.

The improved supporting garments of the present invention include an adjustable brace back member 11, an adjustable waist back member 12, a combined hip and abdominal covering and supporting member 13, a front hose supporting member 14, and a combined bust, hose, and abdominal covering and supporting member 15, together with connecting means hereinafter to be described in greater detail, whereby the brace back member 11, or the waist back member 12 may be used in combination with any one or several of the other members, or in the case of a man in combination with trousers, the several combinations providing bracing and supporting garments adapted to meet the particular requirements of any individual wearer.

30 The improved adjustable brace back member 11 includes half members 11a and 11b, respectively, including laterally spaced inner vertical preferably double stay braced edges 16a and 16b, the double stay braced edges being provided respectively with a plurality of similarly spaced eyelets 17a and 17b.

On the back of the half member 11a, a diagonal double stay brace 18a extends upwardly and outwardly from a location at the bottom edge 19a of the half member 11a 40 preferably midway between the inner edge 16a and the lower outer corner 20a.

A similar stay brace 18b is provided for the half member 11b and the stay brace 18b extends upwardly and outwardly from a location at the bottom edge 19b of the half member 11b preferably midway between the inner edge 16b and the lower outer corner 20b.

50 The diagonal braces 18a and 18b are provided respectively with a plurality of similarly spaced guide eyelets 21a and 21b at the lower end portions thereof.

The half member 11a furthermore includes 55 a curved upper edge 22a terminating at an upper corner 23a from which a curved upper side edge 24a extends outwardly and downwardly to an arm pit corner 25a at which preferably the upper end of the brace 18a terminates. As shown in the drawings, the arm pit corner 25a is preferably located substantially midway between the upper corner 23a and the lower corner 20a.

From the arm pit corner 25a the half member 11a includes a curved lower side edge 26a

which terminates at the lower outer corner 20a.

A shoulder strap 27a is connected at one end with the upper corner 23a, and is provided with a set of longitudinally spaced upper button holes 28a adapted for making connection with one upper corner of the combined bust, hose, and abdominal supporting member 15, as will hereinafter be set forth in greater detail.

Below the set of button holes 28a, the strap 27a is provided with another set of longitudinally spaced button holes 29a adapted for buttoning with the button 30a secured on the outer end of the strap 27a, whereby the outer end may be looped through a preferably bone ring 31a, and the position of the bone ring 31a may be adjusted by selectively buttoning the button 30a in one of the button holes 29a.

The arm pit corner 25a is connected with one end of a preferably elastic brace and connector strap 32a, and the outer end of the brace and connector strap 32a is provided with a set of longitudinally spaced button holes 33a, whereby the strap 32a may be passed through the ring 31a and may be adjustably connected either with a button 34a secured adjacent the corner 20a, or with one upper corner of the front hose supporting member 14, or with one upper corner of the combined hip and abdominal supporting or girdle member 13, as will hereinafter be set forth in greater detail.

Similarly, the half member 11b furthermore includes a curved upper edge 22b terminating at an upper corner 23b from which a curved upper side edge 24b extends outwardly and downwardly to an arm pit corner 25b at which preferably the upper end of the brace 18b terminates.

From the arm pit corner 25b the half member 11b includes a curved lower side edge 26b which terminates at the lower outer corner 20b.

A shoulder strap 27b is connected at one end with the upper corner 23b, and is provided with a set of longitudinally spaced upper button holes 28b adapted for making connection with the other upper corner of the combined bust, hose, and abdominal supporting member 15, as will hereinafter be set forth in greater detail.

Below the set of button holes 28b, the strap 27b is provided with another set of longitudinally spaced button holes 29b adapted for buttoning with the button 30b secured on the outer end of the strap 27b, whereby the outer end may be looped through a preferably bone ring 31b, and the position of the bone ring 31b may be adjusted by selectively buttoning the button 30b in one of the button holes 29b.

The arm pit corner 25b is connected with one end of a preferably elastic brace and

connector strap 32b, and the outer end of the brace and connector strap 32b is provided with a set of longitudinally spaced button holes 33b, whereby the strap 32b may be passed through the ring 31b and may be adjustably connected either with a button 34b secured adjacent the corner 20b, or with the other upper corner of the front hose supporting member 14, or with the other upper corner of the combined hip and abdominal supporting or girdle member 13, as will hereinafter be set forth in greater detail.

A criss-cross brace lacing 35 is passed through the eyelets 17a and 17b and 21a and 21b, as illustrated, adjustably connecting the side edges 16a and 16b together, and diagonal lengths of the lacing 35 pass on the inside of the half members 11a and 11b and out through the eyelets 18a and 18b and are looped respectively through preferably bone rings 36a and 36b which are located respectively adjacent the corners 20a and 20b.

Improved yielding connector means for the lower corners of the brace back member 11 and for the looped rings of the lacing, are preferably provided at one side by means of a preferably elastic connector strap 37a which is secured at one end with the corner 20a, passes through a connector ring 38a, and is secured at its other end with the lacing ring 36a, and at the other side by means of a preferably elastic connector strap 37b which is secured at one end with the corner 20b, passes through a connector ring 38b, and is secured at its other end with the lacing ring 36b.

The improved adjustable waist back member 12 may include a diagonal stay brace 118a extending upwardly and outwardly from a location at the bottom edge 119 of the waist back member 12, at one side of the center thereof, and a similar stay brace 118b extends upwardly and outwardly from the bottom edge 119 at the other side of the center thereof.

The waist back member 12 furthermore includes a curved upper edge 122 terminating at one side at an upper corner 123a from which a curved upper side edge 124a extends outwardly and downwardly to an arm pit corner 125a at which preferably the upper end of the brace 118a terminates.

From the arm pit corner 125a a curved lower side edge 126a extends and terminates at the lower outer corner 120a.

A shoulder strap 127a is connected at one end with the upper corner 123a, and is provided with a set of longitudinally spaced upper button holes 128a adapted for making connection with one upper corner of the combined bust, hose, and abdominal supporting member 15, as will hereinafter be set forth in greater detail.

Below the set of button holes 128a, the strap 127a is provided with another set of longi-

tudinally spaced button holes 129a adapted for buttoning with the button 130a secured on the outer end of the strap 127a, whereby the outer end may be looped through a preferably bone ring 131a, and the position of the bone ring 131a may be adjusted by selectively buttoning the button 130a in one of the button holes 129a.

The arm pit corner 125a is connected with one end of a preferably elastic brace and connector strap 132a, and the outer end of the brace and connector strap 132a is provided with a set of longitudinally spaced button holes 133a, whereby the strap 132a may be passed through the ring 131a and may be adjustably connected either with a button 134a secured adjacent the corner 120a, or with one upper corner of the front hose supporting member 14, or with one upper corner of the combined hip and abdominal supporting or girdle member 13, as will hereinafter be set forth in greater detail.

Similarly, the curved upper edge 122 terminates at the other side of an upper corner 123b from which a curved upper side edge 124b extends outwardly and downwardly to an arm pit corner 125b at which preferably the upper end of the brace 118b terminates.

From the arm pit corner 125b a curved lower side edge 126b extends and terminates at the lower outer corner 120b.

A shoulder strap 127b is connected at one end with the upper corner 123b, and is provided with a set of longitudinally spaced upper button holes 128b adapted for making connection with the other upper corner of the combined bust, hose, and abdominal supporting member 15, as will hereinafter be set forth in greater detail.

Below the set of button holes 128b, the strap 127b is provided with another set of longitudinally spaced button holes 129b adapted for buttoning with the button 130b secured on the outer end of the strap 127b, whereby the outer end may be looped through a preferably bone ring 131b, and the position of the bone ring 131b may be adjusted by selectively buttoning the button 130b in one of the button holes 129b.

The arm pit corner 125b is connected with one end of a preferably elastic brace and connector strap 132b, and the outer end of the brace and connector strap 132b is provided with a set of longitudinally spaced button holes 133b, whereby the strap 132b may be passed through the ring 131b and may be adjustably connected either with a button 134b secured adjacent the corner 120b, or with the other upper corner of the front hose supporting member 14, or with the other upper corner of the combined hip and abdominal supporting or girdle member 13, as will hereinafter be set forth in greater detail.

Improved yielding connector means for the lower corners of the waist back member

12, are preferably provided at one side by means of a preferably elastic looped connector strap 137a which is secured at its ends with the corner 120a and passes through a connector ring 138a and at the other side by means of a preferably elastic looped connector strap 137b which is secured at its ends with the corner 120b and passes through a connector ring 138b.

- 10 The improved combined hip and abdominal supporting member 13 includes a preferably stayed fabric back and hip portion 40, a front or abdominal fabric half portion 41a, a front or abdominal fabric half portion 41b, a preferably elastic fabric portion 42a connected between one side of the back portion 40 and the adjacent side of the half front portion 41a, and a preferably elastic fabric portion 42b connected between the other side of the back portion 40 and the adjacent side of the front half portion 41b.
- 15

The outer side edge 43a of the half front portion 41a is provided as illustrated with a set of longitudinally spaced eyes 44a, and 25 the outer side edge 43b of the front half portion 41b is provided with a set of hooks 44b adapted for connection with the eye 44a, whereby the supporting or girdle member 13 may be put on and taken off by the 30 user.

Rear garters 45a and 45b preferably depend downwardly from the back portion 40.

A fabric flap 46a is preferably provided as an extension of the front half portion 41a 35 and overlaps the elastic fabric portion 42a.

A similar fabric flap 46b is preferably provided as an extension of the front half portion 41b and overlaps the elastic fabric portion 42b.

40 At the upper edge of the flap 46a a button 47a is secured for making selective connection, with one of the button holes of one of the brace and connector straps of either the brace back member 11 or the waist back member 12, and similarly a button 47b is secured at the upper edge of the flap 46b for making selective connection with one of the button holes of the other brace and connector strap of either the brace back member 11 45 or the waist back member 12.

50 Preferably two strap and buckle connectors 48a are secured on the flap 46a and extend therefrom over the back portion 40, and similarly preferably two strap and buckle connectors 48b are secured on the flap 46b and extend therefrom over the back portion 40 and toward the connectors 48a.

The upper connectors 48a and 48b are 55 adapted for making selective connection with the lower connector rings of either the brace back member 11 or the waist back member 12, as is hereinafter set forth in greater detail.

The lower connectors 48a and 48b are 60 adapted for connecting with the combined

bust, hose, and abdominal supporting member 15, as will hereinafter be set forth in greater detail.

The front hose supporting member 14 includes a preferably stayed fabric abdominal covering portion 49 at each upper corner of which is provided a strap and buckle connector 50 for selective connection with the lower connector rings of either the brace back member 11 or the waist back member 12, and each lower corner of the covering portion 49 is provided with a depending pair of garters 51.

The combined bust, hose, and abdominal supporting member 15 includes a bust and abdominal covering and supporting portion 52, having upper corners 53a and 53b, and buttons 54a and 54b are secured respectively to the corners 53a and 53b for button connecting respectively with the upper button holes of the shoulder straps of either the brace back member 11 or the waist back member 12.

A set of garters 55 is secured at each lower corner of the covering portion 52 and tapering tie flaps 56a and 56b extend respectively from opposite sides of the covering portion 52 and are provided at their ends respectively with preferably bone rings 57a and 57b, whereby the flaps 56a and 56b may be overlapped about the back of the user and the rings 57a and 57b connected respectively with strap buckles of either the girdle member 13 or the hose supporting member 14.

Combined buckle strap and eyelet connectors 58 are provided for enabling either the brace back member or the waist back member to be used by a man in connection with trousers.

In Figs. 1 and 2, a woman is illustrated 105 wearing one combination of the improved garment members, including the adjustable brace back member 11, and the front hose supporting member 14, and illustrating the manner of connecting the members together, 110 and one selected connection of the elastic brace and connector straps.

In Fig. 3 a man is illustrated wearing the improved brace back member 11 in connection with trousers and by the use of connectors 58, and with the brace and connector straps connected in their shoulder bracing positions.

In Fig. 6 a woman is shown wearing a combination of the improved garments including the adjustable waist back member 12 and the supporting or girdle member 13.

In Figs. 7 and 8 the combination of the members of Fig. 6 are added to by the use of the combined bust, hose, and abdominal supporting member 15.

The improved garments thus set forth may be selectively combined with each other as aforesaid, are adjustable to substantially any conformation of the user, and by the provision 130

of the yielding connector means as above set forth in detail, the improved garments are comfortable in use, and at the same time correct posture, as desired.

5. I claim:

1. Garments including a back member for fitting against the back of a body, said back member having an upper corner, a lower corner and an arm pit corner located substantially midway between said upper and lower corners, a connector strap having one end connected to said arm pit corner and its other end connected to said lower corner, and a shoulder strap connected at one end to said upper corner and having at its other end a looped sliding connection with said connector strap. 70
2. Garments including a back member for fitting against the back of a body, said back member having an upper corner, a lower corner and an arm pit corner located substantially midway between said upper and lower corners, a yielding connector strap having one end connected to said arm pit corner and its other end adjustably connected to said lower corner, and a shoulder strap connected at one end to said upper corner and having at its other end an adjustable looped sliding connection with said connector strap. 75
3. Garments including a back member and an abdominal covering member, said back member having an upper corner, a lower corner and an arm pit corner located substantially midway between said upper and lower corners, a connector strap having one end connected to said arm pit corner, a shoulder strap connected at one end to said upper corner and having at its other end a looped sliding connection with an intermediate portion of said connector strap, the other end of said connector strap being adapted for selective detachable connection with said lower corner of the back member or with the abdominal covering member, and a yielding connector strap connected at one end to said lower corner of the back member and at its other end to said abdominal covering member. 80
4. Garments including a back member and an abdominal covering member, said back member having an upper corner, a lower corner and an arm pit corner located substantially midway between said upper and lower corners, a yielding connector strap having one end connected to said arm pit corner, a shoulder strap connected at one end to said upper corner and having at its other end a looped adjustable sliding connection with an intermediate portion of said connector strap, the other end of said connector strap being adapted for selective detachable and adjustable connection with said lower corner of the back member or with the abdominal covering member, and a yielding connector strap connected at one end to said lower corner of the back member and adjustably connected at its other end to said abdominal covering member. 85
5. Garments including a back member and an abdominal covering member, said back member having an upper corner, a lower corner and an arm pit corner located substantially midway between said upper and lower corners, a yielding connector strap having one end connected to said arm pit corner, a shoulder strap connected at one end to said upper corner and having at its other end a looped adjustable sliding connection with an intermediate portion of said connector strap, the other end of said connector strap being adapted for selective detachable and adjustable connection with said lower corner of the back member or with the abdominal covering member, and a yielding connector strap connected at one end to said lower corner of the back member and at its other end to said abdominal covering member. 90
6. Garments including a back member and an abdominal covering member, said back member having an upper corner, a lower corner and an arm pit corner located substantially midway between said upper and lower corners, a yielding connector strap having one end connected to said arm pit corner, a shoulder strap connected at one end to said upper corner and having at its other end a looped adjustable sliding connection with an intermediate portion of said connector strap, the other end of said connector strap being adapted for selective detachable and adjustable connection with said lower corner of the back member or with the abdominal covering member, and a yielding connector strap connected at one end to said lower corner of the back member and adjustably connected at its other end to said abdominal covering member. 95
7. In testimony that I claim the above, I have hereunto subscribed my name. 100
